UNITED STATES PATENT OFFICE.

ITHUEL M. JOHNSON, OF CORNING, NEW YORK.

WAGON-JACK.

SPECIFICATION forming part of Letters Patent No. 276,594, dated May 1, 1883.

Application filed March 13, 1883. (No model.)

To all whom it may concern:

Be it known that I, ITHUEL M. JOHNSON, a citizen of the United States of America, residing at Corning, in the county of Steuben and State of New York, have invented certain new and useful Improvements in Wagon-Jacks, of which the following is a specification, reference being had therein to the accompanying drawings.

10 This invention relates to improvements in combined lifting-jack and wrench; and it consists in the combination and construction of parts, substantially as hereinafter more fully set forth.

15 In the accompanying drawings, Figure 1 is a side elevation of my improved lifting-jack. Fig. 2 is a perspective folded view thereof. Fig. 3 is a detailed view of the same, as is also Fig. 4, embodying the wrench.

20 In carrying out my invention I employ two upright pieces, A, pivoted together by the pivot-bolt A' at their upper ends, and adapted to be spread apart at their lower ends, it thus being caused to assume an A shape. The

25 lower ends of these uprights are each provided with a pointed projection, a, and a lateral projection, a', the former being adapted to penetrate the ground and prevent the slipping of the jack and the latter to prevent the sinking 30 of the standards thereinto, while, when the jack, is used indoors, cushions or disks a'', of rubber, are applied to said point-projections to prevent the marring of the floor.

B is the lifting bar or lever, pivoted between the upper ends of the uprights A A, and preferably by the same pivot-bolt used to connect the latter together. The forward slightly hooked end of the lever B, by the action of which the weight or the axle of the vehicle is 40 lifted, is supplied with a rubber band or cushion, b, to avoid defacing nicely-painted axles. This lever and one of the uprights A—the front one—are provided with notches, as at c, with which is adapted to engage a bail, C, improvised into a wrench, C. The bail C has at its upper end, on each side, a hook, C³, adapted to engage with the notches of the lever. By exerting downward pressure upon the longer arm of the lever B and slipping the hook at 45 the upper end of the bail into the desired notch of the lever and the lower end thereof into the required notch of the front bar, A, the lever, with its supported axle or weight, will

be retained in position. The wrench C' of the bail C has a spring, C², arranged to project 55 into its eye, and thus enable the holding of the nut from falling therefrom as the same is being removed by the wrench after having been unscrewed from the axle. The handle of the wrench is provided with a lateral projection or pin, d, which serves as a crank to the convenient turning or operation of the wrench.

When the parts are folded, as shown in Fig 2, it will be noticed that the bail C is slipped 65 upon and buttoned to one of the bars A by means of a button-shaped head, e, on one end of the pivot-bolt A', it being adapted to permit the insertion of the bail between said head or button and the bar A, said button being 70 adapted to be turned so as to secure the bail to the bar. The pin or projection d of the wrench or bail is inserted through the notch f in the edge of one of the bars A and enters a depression or indenture, g, in the other bar 75 A, aiding the securing of the parts compactly together.

I claim and desire to secure by Letters Patent—

1. In a lifting-jack, the combination, with 80 the pivoted-together bars, one being notched, of the notched lever, and the bail having a lateral hook at its upper or one end and on one or both sides, substantially as and for the purpose set forth.

2. In a lifting-jack, the bars having their lower ends provided each with a pointed projection and a lateral projection, substantially as and for the purpose set forth.

3. In a lifting-jack, the bars A, having their 90 pivot-bolt provided with a button-shaped head, e, in combination with the bail c, substantially as and for the purpose set forth.

4. In a lifting-jack, the bars A, with their pivot-bolt provided with a button-shaped head, 95 e, one of said bars also having a notch, f, and the other a recess, g, in combination with the bail C, having the lateral pin or projection d, substantially as and for the purpose specified.

In testimony whereof I affix my signature in 100 presence of two witnesses.

ITHUEL M. JOHNSON.

Witnesses:

JAMES JOHNSON,
FRANK GENUNG.
